AUTOMATIC FREQUENCY CONTROL
CIRCUITS

Oswold Edward Keall, Chelmsford, England, assignor to Radio Corporation of America, a corporation of Delaware

Application October 22, 1937, Serial No. 170,343
In Great Britain December 31, 1936

8 Claims. (Cl. 250—40)

This invention relates to radio and like receivers and more particularly to automatic frequency control systems for use therein. By the expression "automatic frequency control system" (A. F. C. system) as herein employed, is meant a system whereby the tuning of a receiver as a whole is automatically maintained correct for a station to be received when once the said tuning has been set—usually manually—within a predetermined range on either side of the correct tuning position. A. F. C. systems are sometimes (rather loosely) termed "automatic tuning" systems, since a measure of automatic tuning is obtained thereby, although, in fact, the A. F. C. system provides merely accuracy of tuning, selection as between stations being effected by other means, usually an ordinary manually controlled tuning knob.

It is known that if the anode-cathode space of a valve is in effect, included in a tuned circuit, and there is fed to the control grid of said valve an alternating voltage substantially in quadrature with that set up across said tuned circuit, said anode-cathode space will act as though it were a reactance in said circuit and the value of said reactance can be automatically controlled in dependence upon the departures from accurate tuning (so as to correct for said departures) for example by varying the bias on the grid of said valve. The required phase quadrature relationship between the voltage fed to the grid of the valve and that across the tuned circuit is generally, in the known arrangement of this nature produced by means of two series impedances in parallel with the tuned circuit, one being reactive and the other resistive. Such an arrangement, however, offers the defect that the valve throws not only reactance, but also resistance (which is always positive) across the tuned circuit and this resistance is normally of sufficient magnitude to lead to difficulties; for example, where the tuned circuit is required to be that of the local oscillator of a superheterodyne receiver (a common case for A. F. C.) the magnitude of the resistance thrown across the tuned circuit by the valve will generally be sufficient to involve alteration of the design of the local oscillator circuit of which the tuned circuit forms part. This invention provides improved circuit arrangements operating on the principle just described but not involving the defect just mentioned and which are such that if desired the valve may be caused to act as a substantially pure reactance as regards the tuned circuit, although, if desired, the valve may be caused to throw resistance (which may be

either positive or negative) across said circuit. The invention also provides circuit arrangements which, though not free from producing resistance changes as well as reactance changes, have been found to fulfill practical requirements in most cases.

The object of the invention is achieved by deriving the quadrature voltage for the grid of the valve from a portion of a phase splitting network constituting a substantially constant impedance and preferably constituted by two branches in parallel, one branch consisting of an inductance in series with a resistance and the other consisting of a condenser in series with a resistance.

The invention is illustrated in and further explained with reference to the accompanying circuit diagrams wherein each of Figs. 1, 2 and 3 show different modifications of the invention.

Referring to Figure 1 which shows diagrammatically one way of carrying out this invention as applied to a superheterodyne receiver, the local oscillator of said receiver comprises a valve 1—for example, a back coupled triode as shown—having the usual manually tunable circuit 2, 3, in its anode-cathode circuit. Shunted across the anode-cathode space of the local oscillator valve 1 is the anode-cathode space of a control valve 4 which is shown as a variable mu-pentode whose control grid-cathode circuit includes the secondary 5 of a transformer, if desired in series with a capacity-shunted bias resistance combination 6, 7. Coupled to the coil 2 in the local oscillator tuned circuit 2, 3, is a second coil 8 which is included between control grid and cathode of a further valve 9 which is shown as a variable mu-pentode in whose anode circuit is included a phase splitting circuit comprising two branches in parallel, one branch consisting of an inductance 10 in series with a resistance 11 and the other consisting of a condenser 12 in series with a resistance 13. The said condenser and the said inductance have a common point 14 which is connected to the anode 15 of the valve 9 the common point 16 of the two resistances being connected through the usual anode battery (not shown) to the cathode 17 of said valve 9. The control grid-cathode circuit of the valve 9 may also include a capacity shunted bias resistance combination 19, 20. The primary 21 of the transformer having the secondary 5 (this transformer is preferably as indicated at 18 of the type having electrostatically screened windings) is connected at one end to the junction 22 of the inductance 10 and resistance 11 in one branch of the phase

splitting circuit and at the other to the junction 23 of the condenser 12 and resistance 13 in the other branch. The phase splitting circuit is a substantially constant impedance circuit whose resistance is equal to the square root of the quotient obtained by dividing its inductance by its capacity, the resistances 11, 13 being equal and the reactances 10, 12, being so dimensioned that the voltage across the branch 12, 13, is equal to 10 and in quadrature with the voltage across the branch 13, 11, each of these voltages being at 45° phase angle to the voltage between the points 22, 23.

With the above arrangement the alternating voltage applied to the grid of the control valve 4 will in the ideal case be a quadrature with the local oscillator tuned circuit voltage and the said control valve will act as though it were a substantially pure reactance across the local oscillator tank circuit 2-3, the said reactance being either an inductance or a capacity in dependence upon the sense of the coupling between the local oscillator tuned circuit 2, 3, and the grid circuit of the further valve 9. This reactance may be varied over a wide range by varying the mutual conductance of the further valve 9 and/or of the control valve 4, e. g., by varying the bias on one or both of these valves. In practice, this variation is obtained automatically in dependence upon departures of the local oscillator tuning from accuracy and is such as to correct for such departures. The means for automatically producing such variation do not per se, form part of this invention and any of the numerous known means may be employed; e. g., use may be made, as known per se, for A. F. C. purposes, of two sharply tuned circuits one resonant slightly above and the other slightly (and the same amount) below, the correct predetermined intermediate frequency, these circuits being fed from an intermediate stage and feeding into a suitable rectifier arrangement so that, if the intermediate frequency actually produced is above the predetermined value a correcting bias which produces variation in one direction is obtained, while if the actually produced intermediate frequency is lower than it should be, a correcting voltage which produces variation in the other direction is obtained.

By departing slightly from the quadrature condition of the alternating input to the control valve, the said valve may be caused to throw either positive or negative resistance across the local oscillator circuit, the sign of the resistance depending upon the direction of departure. If desired, this action may be made adjustable by utilizing an adjustable condenser for the condenser 12 in the phase splitting circuit in the anode circuit of the valve 9. By suitably interlinking such an adjustable condenser with the normal tuning control knob as shown by dotted line 3', the oscillator amplitude may be caused to remain substantially constant over the tuning range or it may be caused to increase or decrease in accordance with some required predetermined law chosen to suit the particular receiver in question.

In the case of very short wave receivers, where difficulty is often encountered in obtaining an efficient oscillator for frequency changing purposes, the use of the valve to throw negative resistance into the local oscillator circuit may be of substantial advantage.

Although, as above set forth, the valve may be caused to throw resistance into the tuned cir-

cuit as well as reactance, in general, reactance only will be required.

By suitably choosing the value of the impedance of the constant impedance phase splitting circuit, relatively large changes of reactance presented by the valve may be obtained per unit change of mutual conductance of the valve.

In the modification shown in Figure 2, the further valve 9 of Figure 1 is dispensed with and instead there is provided, in shunt with the anode-cathode space of the local oscillator valve 1, a circuit comprising a low reactance condenser 24 (connected to the anodes of the local oscillator and control valves 1 and 4) in series with a high resistance 25 which is in turn in series with a phase splitting circuit as shown in Figure 1. The primary 21 of the screened transformer 21-5 is connected to points in the two branches of the phase splitting circuit, just as in Figure 1. To give a practical example, experimentally tested, the high resistance was about 50,000 ohms and the impedance (constant) of the phase splitting circuit about 1,000 ohms. With these values a change of 9 volts bias on the control valve (which, for this example, was a pentode) produced an effective change of 4 micro-micro-farads across the local oscillator.

Figure 3 shows a modification of the circuit of Figure 2. The difference between Figure 3 and Figure 2 is that in the said Figure 3, the transformer winding 5 is the secondary of an auto-transformer whose primary is constituted by the coil 10 in the phase splitting circuit. In the theoretically ideal case, the voltage across the whole circuit consisting of elements 24, 25, 12, 13, 10 and 11 will be in phase with that across the network 12, 13, 11, 10, and both these voltages will be in quadrature with that between the grid of the valve 4 and the point 16'. This, however, neglects the effects of mutual inductance and leakage.

In all three circuits, the relative position of the elements 10, 11, and also of the elements 12, 13, may be reversed if, for practical reasons, this may be found desirable. Again, in all cases, the ideal constant impedance condition—namely that resistance elements 11 and 13 are equal to one another in value and each equal to the square root of the quotient obtained by dividing the value of the inductance 10 by that of the capacity 12 may be departed from to some extent if, in any particular case, a predetermined resistance variation accompanying reactance variation is required.

By employing a suitable double purpose valve—e. g., a triode-pentode—in lieu of the two valves in the embodiments of Figures 2 and 3 still further simplification can be achieved.

Having now particularly described and ascertained the nature of my said invention and in what manner the same is to be performed, I declare that what I claim is:

1. In combination with a local oscillator provided with a resonant tank circuit, a frequency control tube having said tank circuit included in its space current path, a phase splitting network coupled to said tank circuit and feeding voltage derived from the latter to the input electrodes of the control tube, said network comprising a pair of parallel reactive arms of opposite sign, the voltages developed across the arms being equal and in phase quadrature, said voltage fed to said input electrodes being substantially in quadrature with the voltage across the tank circuit.

2. In combination with a local oscillator pro-

vided with a resonant tank circuit, a frequency control tube having said tank circuit included in its space current path, a phase splitting network coupled to said tank circuit and feeding voltage derived from the latter to the input electrodes of the control tube, said network comprising parallel reactive branches, one branch including capacity and the other branch including inductance, alternating voltages developed across said arms being equal and in phase quadrature, said voltage fed to said input electrodes being substantially in quadrature with the voltage across the tank circuit.

3. In combination with a local oscillator provided with a resonant tank circuit, a frequency control tube having said tank circuit included in its space current path, a phase splitting network coupled to said tank circuit and feeding voltage derived from the latter to the input electrodes of the control tube, said voltage fed to said input electrodes being substantially in quadrature with the voltage across the tank circuit, said network comprising a pair of parallel branches, one branch consisting of a condenser and resistor in series, the other branch consisting of an inductance and resistor in series and the resistance of said network being equal to the square root of the quotient obtained by dividing its inductance by its capacity.

30 4. In combination with a local oscillator provided with a resonant tank circuit, a frequency control tube having said tank circuit included in its space current path, a phase splitting network coupled to said tank circuit and feeding voltage derived from the latter to the input electrodes of the control tube, said network comprising a pair of parallel reactive arms of opposite sign, the voltages developed across the arms being equal and in phase quadrature, said voltage fed to said input electrodes being substantially in quadrature with the voltage across the tank circuit, a second tube having said network in the anode circuit thereof, means coupling said tank circuit to the input electrodes of the second tube.

45 5. In combination with a local oscillator provided with a resonant tank circuit, a frequency control tube having said tank circuit included in its space current path, a phase splitting network coupled to said tank circuit and feeding voltage derived from the latter to the input electrodes of the control tube, said network comprising a pair of parallel reactive arms of opposite sign, the voltages developed across the arms being equal and in phase quadrature, said voltage fed to said input electrodes being substantially in quadrature with the voltage across the tank circuit, and

means for varying the gain of the control tube thereby to adjust the value of reactance simulated across said tank circuit by said control tube.

6. In combination, with the resonant circuit of an oscillator network, means for tuning the circuit over a desired frequency range, a frequency control arrangement comprising a control tube having input and output electrodes, said resonant circuit being connected to the output electrodes of the control tube, a network coupling the resonant circuit to the control tube input electrodes, said network comprising a pair of reactive arms of opposite sign and applying voltage derived from across said resonant circuit to said input electrode but in substantially quadrature relation thereto, means for adjusting the magnitude of one of said arms with adjustment of the tuning means, and means for varying the gain of said control tube.

7. In combination the resonant circuit of an oscillator network, a frequency control arrangement comprising a control tube having input and output electrodes, said resonant circuit being connected to the output electrodes of the control tube, a network coupling the resonant circuit to the control tube input electrodes, said network comprising a pair of reactive arms of opposite sign and applying voltage derived from across said resonant circuit to said input electrode but in substantially quadrature relation thereto, the reactive values of said arms being so chosen that alternating voltages developed thereacross are equal and in phase quadrature, said network being included in a shunt circuit connected across said resonant circuit, and means for varying the gain of said control tube.

8. In combination with a tunable oscillatory circuit which is adapted to cover a relatively wide frequency range, means for supplementally adjusting the tuning of the circuit at desired frequencies of the range, said means comprising an electron discharge device having at least a cathode, control grid and anode electrode, means connecting the cathode to anode impedance of the device across said oscillatory circuit, a phase splitting network comprising at least two reactive branches connected across the said circuit, said network being constructed to develop thereacross an alternating voltage in quadrature with the alternating voltage across said circuit, means for impressing the quadrature voltage between the grid and cathode, and the constants of the said network being chosen to maintain the impedance thereof substantially constant over said range.
